Primary Examiner—Holly H Baynam*(74) Attorney, Agent, or Firm*—Volpe and Koenig P.C.(57) **CLAIM**

The ornamental design for an loop fastener, as shown and described.

DESCRIPTION

FIG. 1 is a front perspective view of an embodiment of a design for an loop fastener according to the present invention; FIG. 2 is a front elevational view of the design shown in FIG. 1;

FIG. 3 is a rear elevational view of the design shown in FIG. 1;

FIG. 4 is a right side elevational view of the design shown in FIG. 1, the left side being a mirror image thereof;

FIG. 5 is a top plan view of the design shown in FIG. 1;

FIG. 6 is a bottom plan view of the design shown in FIG. 1;

FIG. 7 is a front perspective view of the design shown in FIG. 1 shown bent in the longitudinal direction and formed into a loop;

FIG. 8 is a front perspective view of a second embodiment of a design for an loop fastener according to the present invention;

FIG. 9 is a front elevational view of the design shown in FIG. 8;

FIG. 10 is a rear elevational view of the design shown in FIG. 8;

FIG. 11 is a right side elevational view of the design shown in FIG. 8, the left side being a mirror image thereof;

FIG. 12 is a top plan view of the design shown in FIG. 8;

FIG. 13 is a bottom plan view of the design shown in FIG. 8;

FIG. 14 is a front perspective view of a third embodiment of a design for an loop fastener according to the present invention;

FIG. 15 is a front elevational view of the design shown in FIG. 14;

FIG. 16 is a rear elevational view of the design shown in FIG. 14;

FIG. 17 is a right side elevational view of the design shown in FIG. 14, the left side being a mirror image thereof;

FIG. 18 is a top plan view of the design shown in FIG. 14;

FIG. 19 is a bottom plan view of the design shown in FIG. 14.

FIG. 20 is a front perspective view of fourth embodiment of a design for an loop fastener according to the present invention;

FIG. 21 is a front elevational view of the design shown in FIG. 20;

FIG. 22 is a rear elevational view of the design shown in FIG. 20;

FIG. 23 is a right side elevational view of the design shown in FIG. 20, the left side being a mirror image thereof;

FIG. 24 is a top plan view of the design shown in FIG. 20;

FIG. 25 is a bottom plan view of the design shown in FIG. 20;

FIG. 26 is a front perspective view of a fifth embodiment of a design for an loop fastener according to the present invention;

FIG. 27 is a front elevational view of the design shown in FIG. 26;

FIG. 28 is a rear elevational view of the design shown in FIG. 26;

FIG. 29 is a right side elevational view of the design shown in FIG. 26, the left side being a mirror image thereof;

FIG. 30 is a top plan view of the design shown in FIG. 26;

FIG. 31 is a bottom plan view of the design shown in FIG. 26;

FIG. 32 is a front perspective view of a sixth embodiment of a design for an loop fastener according to the present invention;

FIG. 33 is a front elevational view of the design shown in FIG. 32;

FIG. 34 is a rear elevational view of the design shown in FIG. 32;

FIG. 35 is a right side elevational view of the design shown in FIG. 32, the left side being a mirror image thereof;

FIG. 36 is a top plan view of the design shown in FIG. 32; and,

FIG. 37 is a bottom plan view of the design shown in FIG. 32. The broken lines immediately adjacent the shaded areas represent the bounds of the claim and all other broken lines are for illustrative purposes only. None of the broken lines form part of the claimed design.
